UNITED STATES PATENT OFFICE.

HENRY W. GOODNOW, OF WORCESTER, MASSACHUSETTS, ASSIGNOR OF ONE-HALF TO
JOHN P. RYAN, OF WORCESTER, MASSACHUSETTS.

MATCH-BOX HOLDER.

1,274,409.

Specification of Letters Patent. Patented Aug. 6, 1918.

Application filed March 19, 1917. Serial No. 155,718.

To all whom it may concern:

Be it known that I, HENRY W. GOODNOW, a citizen of the United States, residing at Worcester, in the county of Worcester and 5 State of Massachusetts, have invented a new and useful Match-Box Holder, of which the following is a specification.

This invention relates to a match-box holder by the use of which a box of safety 10 or parlor matches may be conveniently supported.

It is the general object of my invention to improve the construction of such devices as heretofore known and to provide a match-15 box holder possessing advantages in economy of manufacture and in convenience and effectiveness in use which will plainly appear in the following specification.

My invention further relates to arrangements and combinations of parts as herein-after described and specifically pointed out in the appended claims.

The preferred form of my invention is shown in the drawings, in which—

25 Figure 1 shows a match-box holder in use and mounted upon a display-card;

Fig. 2 is a perspective view of my improved holder;

Fig. 3 is a sectional front elevation of the 30 holder and a supported match-box;

Fig. 4 is a sectional side elevation of the holder in use;

Fig. 5 is a top plan view showing the holder folded, and

35 Fig. 6 is a sectional elevation of a modification.

My improved match-box holder comprises sides 10 and 11, a front 12 and a back 13, these parts being hinged together at their 40 vertical edges to form an open-ended rectangular casing. The holder may be formed of any suitable sheet material, but is commonly made by scoring a piece of thin cardboard and gumming the opposite ends of 45 the piece of cardboard together to complete the rectangular casing.

One important advantage of this construction lies in the fact that it can be folded flat when not in use, as shown in Fig. 5, in 50 which condition it is well adapted for convenient shipment and storage.

In one or both of the sides 10 and 11 I form a slot 14 by making a U-shaped cut or slit therein. By this same operation I 55 form an upwardly extending tongue 15 which

remains attached to the box side at its lower end. In the preferred form of my invention the tongue is folded transversely, as clearly shown in Fig. 3, and the upper portion is bent downward and inward, and is 60 gummed to the back of the lower portion. I also prefer to form the line of fold slightly below the center of the tongue, in which event the folded portion of the tongue extends below the base of the tongue and may 65 be gummed to the inside of the box, thereby strengthening the tongue at its base.

If the stock is of sufficient stiffness, however, I may omit the folding and gumming of the tongue, merely cutting off the tongue 70 to the correct length for supporting the inner member of the match-box, as shown in Fig. 6.

Having formed the tongue on one or both sides of the holder, the match-box may be 75 inserted, as clearly shown in the drawings, the outer member or cover of the box passing downward inside of the holder but outside of the tongue, and being supported between the tongue and the side of the box, 80 while the inner member or box proper is supported in raised position upon the ends of the tongues, thus bringing the matches into convenient position for removal. At the same time the scratching surface upon 85 the sides of the match-box is exposed through the slot or slots 14 so that the matches may be lighted after removal from the box.

The match-box holder thus described may be secured to a display-card 16 by gumming 90 its back thereto, or it may be provided with ears 17 and 18 formed by U-shaped cuts in the back. The ears thus formed are bent upward and downward, as shown in Figs. 3 and 4, and provide means by which the 95 holder may be readily secured to a wall or other surface by tacks or similar fastening devices. The front of the holder is adapted to receive advertising matter of any desired kind which may be printed thereon while 100 the holder is in flat unfolded condition.

Having thus described my invention it will be clear that I have invented a match-box holder which can be formed from a single piece of rectangular sheet material by 105 the simple process of making one or more U-shaped slits in said sheet and without the use of any additional material whatever.

Having thus described my invention and a modification thereof, it will be evident 110

that other changes and modifications can be made therein by those skilled in the art without departing from the spirit and scope of my invention as set forth in the claims, 5 and I do not wish to be otherwise limited to the details herein disclosed, but what I claim is—

1. A match-box holder comprising two sides, a front, and a back, all of sheet material and hinged together at their vertical edges to form an open-ended rectangular casing, one of said sides having a slot formed therein by a substantially U-shaped cut, and the partially severed portion forming a 15 tongue effective to support both the outer and inner members of the match-box at different elevations, the scratching surface of said box being exposed through said slot.

2. A match-box holder comprising two sides; a front, and a back, all of sheet material and hinged together at their vertical edges to form an open-ended rectangular casing, one of said sides having a slot formed therein by a substantially U-shaped cut, and 25 the tongue formed by said cut being folded

transversely and the folded portions being gummed together to form a support effective to hold the inner and outer members of the match-box at different elevations, the scratching surface of the box being exposed 30 through said slot.

3. A match-box holder comprising two sides, a front, and a back, all of sheet material and hinged together at their vertical edges to form an open-ended rectangular casing, one of said sides having a slot formed 35 therein by a substantially U-shaped cut, and the tongue formed by said cut being folded transversely at a point below the center of its length and having the upper portion 40 gummed to the inner side of the lower portion and to the inner surface of the box below the U-shaped cut, the support thus formed extending upwardly inside the box cover when in use, and supporting the inner 45 box member in raised position.

In testimony whereof I have hereunto affixed my signature.

HENRY W. GOODNOW.
